CHILD'S SWING

Edwin E. Foster, 1801 Camp Craft Road,
P.O. Box 714, Austin, Tex. 78746

Filed Apr. 11, 1972, Ser. No. 243,116

Term of patent 14 years

Int. Cl. D6—06

U.S. Cl. D6—10

FIG. 1 is a side elevational view of a child's swing showing my new design.

FIG. 2 is a front view thereof.

FIG. 3 is a back view thereof.

FIG. 4 is a side elevational view from the right hand side of FIG. 2.

FIG. 5 is a top plan view thereof.

I claim:

The ornamental design for a child's swing, as shown.
